UNITED STATES PATENT OFFICE.

FREDERIC S. SEAGRAVE, OF DETROIT, MICHIGAN.

PROPELLING ATTACHMENT FOR CHILDREN'S VEHICLES.

1,425,220.

Specification of Letters Patent. Patented Aug. 8, 1922.

Application filed March 8, 1920. Serial No. 364,190.

To all whom it may concern:

Be it known that I, FREDERIC S. SEAGRAVE, a citizen of the United States of America, residing at Detroit, in the county of Wayne 5 and State of Michigan, have invented certain new and useful Improvements in Propelling Attachments for Children's Vehicles, of which the following is a specification, reference being had therein to the accompanying drawings.

This invention relates to means for propelling a child's vehicle, such as a cart, wagon, or other device adapted to support the child's weight and which is adapted to have a forward movement imparted thereto through the medium of an attachment operated by the child.

It is the object of this invention to provide a very simple device for the purpose which is cheap to manufacture, having a minimum number of parts and embodying no springs or other parts liable to break or get out of order, and wherein the construction is such that a backward pull upon the handle portion puts a pressure upon the ground engaging member or members proportionate to the power exerted and a forward movement of said portion lifts said member or members out of contact with the ground without the intervention of separate guiding or lifting means. A further object is to provide certain other new and useful features in the construction and arrangement of parts, all as hereinafter more fully described.

With the above and other ends in view, the invention consists in the matters hereinafter described and more particularly pointed out in the appended claims, reference being had to the accompanying drawing

in which

Fig. 1 is a perspective view of a child's wagon, or cart with the attachment embodying the invention in operative position thereon;

Fig. 2 is a plan view of the same;

Fig. 3 a longitudinal sectional detail of a ground engaging member; and

Fig. 4 a transverse vertical sectional detail thereof.

As shown in the accompanying drawing, the propelling attachment embodying the

invention is shown attached to the upper edge of the body of box 1 of a four wheeled cart or wagon, but it will be understood that this attachment may be applied to other types or forms of children's vehicles.

The attachment comprises a rocker member 2 formed of a single rod or the like bent into substantially U-shape with the free ends of the vertical side members or arms 3 bent inwardly to form pivots 4 adapted to engage openings in a pusher member 5 which pusher member, in a similar manner, is formed from a single rod or the like bent into U-form to provide side legs 6 connected at their upper ends by a cross connecting portion 7 forming a hand hold portion to be grasped by the user. The openings to receive the indent ends 4 of the rocker member 2, are formed in the legs 6 intermediate their ends or at a short distance below the hand hold portion 7, and that portion of each of said legs between their points of pivotal connection with the rocker member and their upper ends where they are connected by the portion 7, is preferably bent or curved upwardly. The cross connecting portion 8 of the rocker member 2 connects the side arms 3 of said member and extends across the box 1. Suitable bearing members or straps 9 embrace the cross member 8 near the angle connection of the arms 3 thereto and these bearings consist of sheet metal straps bent around the rod with the superposed ends of the straps secured by screws, bolts or other fastening means to the upper edges of the box.

When the attachment is used to propel a child's vehicle over a hard smooth surface, such as sidewalk or pavement, the lower ends of the legs 6 are provided with suitable contact members or feet 10 as shown, such feet each comprising a rectangular block 11 having a recess 12 in the upper side thereof to receive the preferably flattened and rounded lower end of the leg 6 having a hole therein and forming an eye 13 to receive a pivot pin 14 engaging a transverse hole in the block. A suitable facing 15 of rubber or other suitable material to frictionally adhere to the surface of the pavement and prevent slippage, extends across the full length and

- width of the bottom or lower face of the block and upward and over the ends thereof, the end portions of the strip or facing being extended inward from the ends of the block 5 upon the top thereof and secured in place by a cap plate 16 secured to the top of the block by screws 17 or other suitable fastening means for drawing the plate toward the block and clamping the ends of the rubber strip between it and the block. This plate has a hole or slot 18 therein through which the end of the rod or leg 6 extends and each side edge of the plate is turned downwardly at right angles to provide side flanges 19 engaging the sides of the block and covering the ends of the hole therein for the pivot pin 14 so that the pin is prevented from slipping out endwise.
- The foot may be quickly detached from 20 the leg by taking out the two screws 17, when the plate may be lifted sufficiently to permit of the removal of the pivot pin, and if found desirable the rubber facing may be quickly removed by loosening said screws 25 to release the ends of the facing strip and a new strip may be quickly secured in its place.
- The rocker member 2 forms a pivotal support and carrying member or guide for the 30 pusher member 5 and as the legs 6 of the pusher extend upwardly beyond their pivotal connection with the arms 3 of the rocker member and are provided with the cross connection forming the hand hold, when a pull is exerted by the child upon this hand hold, the tendency of such force is to turn the legs upon their pivotal connection with the rocker arms and force the feet 10 into firm frictional contact with the pavement, 35 and this frictional contact is in proportion to the force exerted by the operator in swinging the rocker rearwardly with the feet in contact with the pavement, which swinging movement causes a forward movement of the wagon.
- When the child pushes forward upon the 40 hand hold in swinging the rocker forwardly so that the feet may be brought into engagement with the pavement in an advanced position as the wagon rolls forward, the tendency of such force will be to turn the legs 6 upon their pivotal connection with the rocker arms and lift the foot from the pavement, and thus the lower ends of the legs 45 and attached feet are raised and lowered as the rocker is swung forward and backward. This raising and lowering movement is accomplished and the feet held in firm contact with the pavement, without the necessity for springs or means other than the two pivotally connected members, and a 50 very simple, cheap and durable construction is secured which may be very readily attached to a child's vehicle of any description, thus providing a propelling attachment

which may be sold separate from the wagon or other vehicle and readily attached thereto by an unskilled person.

Obviously the device may be constructed of other material than round rods bent into proper form and the pusher and rocker member may have but a single leg and arm instead of being made in the double or U-form as shown.

Other obvious changes may be made in 75 the device within the scope of the appended claims and I do not therefore limit myself to the particular construction and arrangement shown.

Having thus fully described my invention 80 what I claim is:—

1. A propelling attachment for vehicles comprising a pair of rocker arms adapted to be pivotally attached to a vehicle, and a substantially U-shaped pusher member providing side legs and a connecting hand-hold portion, said legs being pivotally attached to the upper ends of said rocker arms at points adjacent the hand-hold portion. 85

2. A propelling attachment for vehicles comprising a pair of substantially U-shaped members, the free ends of one member being pivotally connected to the side legs of the other member intermediate the ends of said legs. 90

3. A propelling attachment for vehicles comprising a substantially U-shaped pusher member providing side legs and a portion connecting the legs and forming a hand-hold, rocker arms pivotally attached at one 100 end to said legs of said pusher member intermediate the ends thereof and adjacent said hand-hold portion, and means for pivotally attaching the opposite ends of said rocker arms to a vehicle. 105

4. A propelling attachment for vehicles comprising a pusher member formed of a continuous piece bent into substantially U-shape to provide side legs and a connecting portion forming a hand-hold, said side legs 110 being formed with openings intermediate their ends, a rocker member formed of a continuous piece bent into substantially U-shape to provide side arms, the ends of said arms being inturned to engage in the openings in said legs and pivotally connect the members, and means engaging the connecting portion of the rocker member adjacent the arms thereof for pivotally attaching said member to a vehicle. 115

5. A propelling attachment for vehicles comprising a rocker member, a pusher member pivotally connected to the rocker member and forming a pair of pusher legs, a block for the lower end of each leg having a 125 recess in the upper side thereof to receive the end of the leg and a transverse opening intersecting the recess, a pivot pin in the opening extending through an opening in the end of the leg to pivotally attach the 130

block to the leg, a contact strip wrapped around the block with its ends overlapping the top of the block, a plate covering said ends and having side flanges engaging the sides of the block and covering the transverse opening therein, and means for securing the plate to the block.

In testimony whereof I affix my signature in the presence of two witnesses.

FREDERIC S. SEAGRAVE.
